FOREIGN PATENT DOCUMENTS

CN 305688934 * 4/2020 ..... 15/5 |*Primary Examiner* — John R Yeh*(74) Attorney, Agent, or Firm* — Gary J. Foose(57) **CLAIM**

The ornamental design for a cleaning device, as shown and described.

DESCRIPTION

FIG. 1 is a front perspective view of a cleaning device embodying our new design;

FIG. 2 is a front view thereof;

FIG. 3 is a left side view thereof;

FIG. 4 is a back view thereof;

FIG. 5 is a right side view thereof;

FIG. 6 is a top view thereof; and,

FIG. 7 is a bottom view thereof.

The broken lines in the drawings depict portions of the cleaning device that form no part of the claimed design.

1 Claim, 4 Drawing Sheets(56)
